UNITED STATES PATENT OFFICE.

ARCHIBALD F. REDDIE, OF PHILADELPHIA, PENNSYLVANIA, ASSIGNOR TO McCALLUM & McCALLUM, OF SAME PLACE.

DESIGN FOR CARPET.

SPECIFICATION forming part of Design No. 25,300, dated March 24, 1896.

Application filed February 24, 1896. Serial No. 580,533. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for Carpet or other Fabrics, of which the following, taken in connection with the accompanying drawing, is a specification.

10. The design of my invention may be fully represented by illustration. Accordingly for a description of it reference is made to the accompanying drawing, in which—

15. A is the body, B the border, and A and B the complete carpet.

20. My design may be produced in various colors or combinations of colors and applied to Brussels, Wilton, velvet, and other carpet fabrics, and its leading or characteristic feature or features may be said to comprise wreath-like ornaments a, surrounding floral sprays b and contrasted with scattered floral ornaments, the whole being displayed upon a background c and associated with bands e.

What I claim as new, and desire to secure 25 by Letters Patent, is—

1. In the design for a carpet the body A, substantially as shown.
2. In a design for a carpet the border B, substantially as shown.
3. The design for a carpet consisting of the body A, and the border B, substantially as shown.

30. In testimony whereof I have hereunto signed my name in the presence of two witnesses.

ARCHIBALD F. REDDIE.
